UNITED STATES PATENT OFFICE

JOHN L. C. HEINZ, OF CHICAGO, ILLINOIS

CASEMENT-WINDOW HINGE

Application filed August 24, 1929. Serial No. 388,073.

This invention relates to a casement window hinge.

One of the main objects of this invention is to provide a hinge which includes means for positively lifting and lowering a casement window sash, with respect to the window sill, and which hinge comprises a minimum of parts constructed so that it is strong and durable and can be placed on the market at a very reasonable price. A further object is to provide a simply and economically constructed hinge which includes means for positively lifting a casement window sash above its sill and then swingably supports it, and for again positively lowering said sash behind the sill and holding it securely locked in such lowered position.

These and other objects and advantages are attained with this invention, as will become apparent from the following description, taken in connection with the accompanying drawings, in which

Fig. 1 is a front elevation of a casement window, viewed from the inside of the building and showing one window sash open and the other sash closed, having my improved hinge applied thereto.

Fig. 2 is a vertical cross-sectional view, on line 2—2 of Fig. 1, with the window sash in the closed position.

Fig. 3 is a side elevational view of the hinge, viewed similar to Fig. 2 but on an enlarged scale, in the sash-lowered position.

Fig. 4 is a view similar to Fig. 3, but showing the parts in the sash-raised position.

Fig. 5 is a horizontal sectional view, taken on line 5—5 of Fig. 3.

In the drawings I have illustrated an embodiment of my invention, in connection with a casement window including the window sashes 11 and 12 mounted in the window frame 13, to be dropped behind the window sill 14 into the closed position, and to be raised above the sill and swung into the room.

My present economically constructed and improved hinge, as illustrated in the drawings, preferably comprises a pair of hinge members or leaves 15 and 16, which are arranged to swing on each other and to slide longitudinally on each other, in the direction

of the axis of their pintle connecting means. In this form of construction the hinge member or leaf 15 is adapted and arranged to be secured to the window frame 13, as with screws 17; while the companion member or leaf 16 is preferably arranged in the shape of an angle member which has the main part thereof provided with a portion 16' which extends at right-angles from said main part, said portion 16' being arranged for receiving suitable screws 18 to secure said leaf to the sash.

The connecting means or pintle means for connecting the leaves 15 and 16 comprises a pair of spaced pintle barrels or knuckles 20 which project from the inner edge or connecting edge of leaf 15, being preferably positioned adjacent the corners on one edge of said leaf and being formed integral therewith. The pintle elements herein consist of a pair of spaced pintles 21 which are secured to the edge of the other hinge leaf 16, by a pair of spaced pintle securing means 22 projecting from the inner edge or connecting edge of leaf 16, said securing means being preferably in the form of pintle barrels placed one at each side of the middle of said edge and integral therewith. These pintles 21 are preferably threaded or removably mounted in said securing means or barrels 22, to provide for inserting the pintles in the barrels 20 during assembling of the hinge leaves, and also to enable disassembling of said leaves for the interchange of either one thereof in case of breakage.

An operating lever 23 is pivotally mounted or fulcrumed by a pin 24 onto the side of hinge leaf 15, adjacent the connecting edge of said leaf and at the intermediate part thereof. Operating means is mounted on the side of said lever, to project therefrom and operate between the spaced pintles 21 and their spaced securing means 22, for sliding said pintles in the outer barrels 20 and to move one hinge leaf longitudinally on the other. Said operating means preferably includes a screw member 25 threaded and secured to the lever 23, and a collar 26 movably or turnably carried on said screw member to operate and slide between said pintle se-

curing elements 22, for raising and lowering leaf 16 and the sash upon the swinging of the lever.

Notch means is furthermore provided in the leaves to allow for a greater swinging movement of the lever, in order to positively retain said lever and leaf 16 and the sash in either the raised or in the lowered position. This notch means preferably comprises a pair of notches 27 provided in the connecting edge or inner edge of leaf 15, one adjacent each side of pivot pin 24; and a notch 28 provided at the middle part in the connecting edge or inner edge of leaf 16, and extending from the space between the pintle securing elements 22 into the leaf edge, as shown in Figs. 3 and 4. With this notch means the lever is enabled to be swung substantially vertically downwards, as shown in Figs. 1 and 3, for positively retaining the sash in the lowered or closed position; or to be swung substantially vertically upwards, as shown in Fig. 4, for positively supporting the sash and the hinge leaf 16 in the raised position.

The parts of this hinge are made symmetrical, so that it can be used interchangeably on either the right hand sash or on the left hand sash; and the construction is very durable and simple, so that the hinge can be placed on the market at a very reasonable price.

An upper hinge, suitable for use with my improved hinge, may be simply constructed and include a hinge part 30 secured to the frame, and a hinge part 31 secured to the sash and connected to said part 30 to permit swinging and sliding movement of said part 31 and of the sash on said part 30 and the frame.

What I claim as my invention and desire to secure by Letters Patent is:

1. A hinge comprising a pair of leaves which are connected to slide longitudinally and to swing on each other and which contain notch means at the connected edges, spaced elements on the connected edge of one leaf, a lever fulcrumed adjacent the edge on the other leaf, and operating means on said lever to operate between said spaced elements for sliding one leaf longitudinally on the other and to move in said notch means for positively retaining the one leaf at either end of its longitudinal movement on the other.

2. A hinge comprising a pair of leaves, one thereof having a pair of pintle barrels on one edge, adjacent the ends of said edge, the other leaf having a pair of pintle barrels adjacent the intermediate part of one edge and having a pair of pintles mounted therein and extending therefrom to slide in said outer barrels on the first said leaf, there being a notch extending from the space between said intermediate barrels into the edge of

the leaf, and there also being a pair of spaced notches in the edge of the first said leaf, and a lever pivoted onto the side of the first said leaf, between said pair of notches, and carrying operating means thereon to operate between said intermediate barrels and the pintles therein for sliding said leaves on each other, said operating means being further slideable into said notches by the final swinging of said lever for positively holding the one leaf at either end of its sliding movement on the other leaf.

3. A hinge comprising a pair of leaves connected to slide longitudinally and to swing on each other, the first leaf containing spaced pintle barrels on one edge, the second leaf containing a pair of alined pintles and means for mounting them spaced on the leaf edge to slide in said pintle barrels on the first leaf, there being a notch in the edge of the leaf and extending from the space between said pintles and their mounting means, also notch means in the first leaf, and a bar-like lever and a pivot pin extending from the side of the first leaf through the end of said lever for pivoting the lever against the side of said leaf, said lever carrying a pin having a collar turnable thereon to operate between said pintles and their mounting means and to move into said notch and notch means, for positively sliding one leaf on the other and for positively retaining it at either end of its longitudinally sliding movement.

In testimony whereof I have signed my name to this specification.

JOHN L. C. HEINZ.
